UNITED STATES PATENT OFFICE.

LE ROY MORAND, OF NEWARK, NEW JERSEY.

ADVERTISING-HOLDER.

No. 853,108.

Specification of Letters Patent.

Patented May 7, 1907.

Application filed May 5, 1906. Serial No. 315,388.

To all whom it may concern:

Be it known that I, LE ROY MORAND, a citizen of the United States of America, residing at Newark, in the county of Essex and State of New Jersey, have invented new and useful Improvements in Advertising-Holders, of which the following is a specification.

The invention relates to an improvement in advertising holders designed primarily for ready and convenient application to street car straps or similar devices and adapted when in position to removably support a card bearing desired advertising data.

The main object of the present invention resides in the production of a holder of the class described constructed of sheet metal and formed to permit its ready attachment to or disengagement from the strap.

The invention will be described in the following specification, reference being had particularly to the accompanying drawings, in which:—

Figure 1 is a view in front elevation of a holder constructed in accordance with my invention, Fig. 2 is a view in rear elevation of the holder and strap. Fig. 3 is a section on line 3—3 of Fig. 2.

Referring particularly to the drawings my holder is constructed of a single strip of sheet metal of the desired size, as 1, the lower and side edges of which are formed in return bends to provide flanges 2 extending parallel with and spaced from the base 1 of the holder. The holding flanges are coextensive with the side and bottom edges of the holder and provide for engaging the edges of the advertising card to maintain the same in relatively fixed relation to the holder. The upper edge of the holder is, of course, free of the retaining flange to provide for the ready insertion of the cards, and if desired the flanges may be so spaced from the base of the holder as to permit the insertion of any desired number of cards at one time, so that in changing the advertisement it will be only necessary to withdraw the outermost cards.

The means by which the holder is secured to the strap is preferably formed integral with the holder, and is arranged in duplicate in alinement longitudinally of the holder and equally spaced above and below the transverse center, as clearly shown in Fig. 1. Said means consists in cutting the body of the holder in triangular outline in two distinct positions longitudinally of the holder, as at 3 and 4. The base of the respective cut

portions remaining integral with the body of the holder so as to provide triangular shaped tongues 5. By preference the respective tongues of the holding means project in opposite directions, that is the connections between said tongues and the body of the holder are arranged on opposite sides of the longitudinal center of the holder, so that the free end of one tongue is alined with the connected end of the adjacent tongue. Furthermore, the triangular tongue is in the nature of a right angle triangle with the hypotenuse of each tongue extending in parallel relation and adjacent the hypotenuse of the other tongue. The extreme upper and lower edges of the two tongues considered as a single fastening means are therefore at right angles to the length of the holder, and in consequence at right angles to the length of the strap. The tongues 5 of each respective fastening means are spaced a slight distance apart longitudinally of the holder, thereby providing a strip 6 bounded on its upper and lower edges by the hypotenuse of the triangular cuts, so that the strip extends diagonally across the holder. The triangular cuts 3 and 4 are preferably so formed as to leave roughened edges on the holder and on the tongues.

In use the strap 7 is placed longitudinally of the holder and in rear thereof in contact with the body, the tongues 5 having been bent in reverse directions to permit the insertion of the strap therebetween. After placing the strap in position the tongues are bent to embrace the strap in rear thereof, the roughened edges of said tongues and of the openings and strips 6 aiding materially in providing a comparatively secure fastening for the holder. The tongues 5 are preferably of greater length than the width of the strap, so as to permit the free ends of said tongues to embrace one side edge of the strap, as clearly shown in Fig. 2, whereby to further secure the same in place. The advertising cards or similar articles are then inserted in the holder, and may if preferred be fixed therein by pressure upon the flanges 2 to clamp the cards between the body of the holder in said flanges.

It will be noted that by the improved fastening described the forward face of the holder is free of obstruction permitting the ready insertion and withdrawal of the cards when desired.

The holder is preferably formed integral

from a strip of sheet metal of an appropriate size, though it is to be understood that it may be as readily formed of separate pieces and such is contemplated as within the scope of the present invention.

Having thus described the invention what is claimed as new, is:—

An advertising holder comprising a plate having marginal flanges spaced from the body of the plate to receive and support the advertising cards, said plate being cut out to provide a series of tongues connected at respectively opposite ends with the body of the plate, the free end of one tongue being alined

with the connected end of the adjacent tongue, the tongues being of right angle triangle shape with their relatively remote edges extending directly transverse the plate, and their approximate edges being in parallel relation and inclined relative to the transverse line of the plate.

In testimony whereof, I affix my signature in presence of two witnesses.

LE ROY MORAND.
